(57) **CLAIM**

The ornamental design for a container for transport of solid goods, as shown and described.

DESCRIPTION

FIG. 1 is a top, front and right side view of a first embodiment of a container for transporting solid goods, showing my new design;

FIG. 2 is a bottom, front and left side view thereof;

FIG. 3 is a right side view thereof, with the left side being a mirror image thereof;

FIG. 4 is a front view thereof, with the back side being a mirror image thereof;

FIG. 5 is a top view thereof;

FIG. 6 is a bottom view thereof;

FIG. 7 is a top, front and right side view of a second embodiment of a container for transporting solid goods, showing my new design;

FIG. 8 is a bottom, front and left side view thereof;

FIG. 9 is a right side view thereof, with the left side being a mirror image thereof;

FIG. 10 is a front view thereof, with the back side being a mirror image thereof;

FIG. 11 is a top view thereof; and,

FIG. 12 is a bottom view thereof.

1 Claim, 12 Drawing Sheets
